L. H. DARROW

ELECTRIC SIGNALING SYSTEM

Filed Jan. 30, 1920

UNITED STATES PATENT OFFICE.

LEO H. DARROW, OF NEW YORK, N. Y., ASSIGNOR TO AMERICAN TELEPHONE AND TELEGRAPH COMPANY, A CORPORATION OF NEW YORK.

ELECTRIC SIGNALING SYSTEM.

Application filed January 30, 1920. Serial No. 355,173.

To all whom it may concern:

Be it known that I, LEO H. DARROW, residing at New York, in the county of New York and State of New York, have invented 5 certain Improvements in Electric Signaling Systems, of which the following is a specification.

This invention relates to electric signaling systems and more particularly to a busy test 10 arrangement connected with the operator's telephone set of a cord circuit adapted for use with the said signaling systems.

In the busy test circuit heretofore used having an operator's telephone set common 15 to all the cord circuits of a particular position, it has been customary to employ a single relay in the busy test lead of the telephone set. This relay was designed to operate whenever the tip of a plug of a cord was 20 brought in contact with an energized sleeve of a jack connected with a busy line. As is well known it is customary to terminate a line in a plurality of jacks into any of which a plug of a cord circuit might be inserted, 25 and the insertion of a plug into one of the jacks raises the potential of all the sleeves of the jacks connected with the same line. When the tip of a plug is brought in contact with one of the sleeves, current will flow over the 30 tip conductor of the cord circuit and through the winding of the relay associated with the busy test lead, which results in the closing of a local circuit whereby current of the desired magnitude flows through the receiver 35 of the operator's telephone set. Trouble has been experienced in maintaining the said relay so accurately adjusted that it will close the local circuit whenever and as often as the tip of the plug is brought in contact with 40 the sleeve of a jack of a busy circuit. One of the objects of the present invention is to provide a busy test system which does not require the use of a relay to close the local circuit through the operator's telephone set, 45 thereby avoiding the maintenance and operating difficulties which have resulted from the use of such a relay.

Another object of this invention is to provide a busy test system having such impedance to the flow of current that a marginal relay associated with the sleeve contact of

said jacks, and controlled by the cord circuit that is connected with one of said jacks, will not be inadvertently released by the diversion of current through the busy test circuit of other cord circuits when a plurality of busy tests are made substantially simultaneously.

The objects of the invention and the invention itself will be made clear from the 60 following description of the invention when read in connection with the attached drawing, which shows one embodiment of the invention.

In the drawing L_1 represents a telephone 65 trunk line extending from an office A to another office or a private branch exchange B, terminating therein in a plurality of jacks J_1 , J_2 , and J_3 . At the office B is a cord circuit X of a well known 70 type which terminates in the plug P_1 adapted for insertion in the jack J_1 and in the plug P_4 , which may be inserted in the jack of a subscriber's line or other signaling circuit. X_1 and X_2 represent only the busy 75 test circuits of two cord circuits similar in this and all other respects to the complete cord circuit X , which terminate in the plugs P_2 and P_3 , adapted for insertion in any of the jacks J_1 , J_2 or J_3 , but are shown associated with jacks J_2 and J_3 in order that the 80 objects of this invention may be made clearer. The cord circuit X has associated therewith an operator's telephone set T_1 , which is adapted for connection with the tip 85 and ring side of the cord circuit by the operation of the listening key K_1 . The telephone set T_1 has associated therewith a receiver R_1 which is connected in series with one of the windings of the induction coil 1. 90 Another winding of said coil is connected with the transmitter to which current is supplied by the operation of the key K_1 . Bridged across the receiver R_1 is one of the windings 95 of the transformer 2, the other winding of said transformer being connected in series with the condenser C_3 , which is in turn connected by means of the conductors 4, 5, and 6 and a contact of relay R_2 with the tip contact of the plug P_1 . A resistance 7 the magnitude of which is preferably fairly high is connected in parallel with the condenser C_3 .

in order to effect the discharge of the said condenser. In the circuits X_1 and X_2 are shown the details of the busy test arrangement which has just been described in connection with the cord circuit. Associated with the cord circuit X are the relays R_2 and R_3 , which are designed when operated to connect together the tip conductors of the two cords of the circuit, and to disconnect the conductor 5 from the tip conductors of the cord circuit. Associated also with the cord circuit X are the supervisory lamps S_1 and S_2 , and the relays R_9 and R_{10} respectively which control the operation of the said lamps.

Associated with the line L_1 at the office A is a cord circuit comprising a source of talking current B_1 which is connected to the line L_1 whenever the plug P_5 of the cord circuit is connected with the jack J_4 of the line L_1 . This cord circuit at A has associated therewith a source of ringing current G_1 by means of which signals may be transmitted to the terminal B. Associated with the line L_1 at the office B are the relays R_4 , R_5 , R_6 , R_7 , R_8 , and an impedance coil 8. Also associated with the line L_1 is the lamp S_8 which responds to signals transmitted from A to B.

This invention will be better understood from the following description of the method of its operation. If the cord circuit at A is connected with the line L_1 by the insertion of plug P_5 in jack J_4 and ringing current is applied to the ring side of the line L_1 by the operation of generator G_1 the ringing current will pass through the condenser 9, contact 10 and winding of the relay R_4 , contact 11 of the relay R_7 to ground, causing the operation of the relay R_4 . By the closing of the contacts of relay R_4 current will flow from the battery B_2 , one winding of relay R_5 , contact 12 of relay R_4 , winding of relay R_4 , contact 11 of relay R_7 to ground, thereby locking relays R_4 and R_5 . The lamp S_2 will be lighted by the flow of current from battery B_3 , lamp S_3 , conductor 13, contact 14 of relay R_4 and one of the windings of the marginal relay R_5 to ground. Upon the lighting of the lamp S_2 the operator at B inserts the plug P_1 of the cord circuit X in the contact J_1 with the listening key K_1 in its operated position. This operation results in the flow of current from the battery B_4 associated with the key K_2 over conductors 16 and 17, the winding of relay R_2 , sleeve contacts of the plug P_1 and jack J_1 and through the complete winding of relay R_6 to ground, causing the operation of relays R_2 and R_6 the latter of which closes its contact 18 and thereby causes the operation of relay R_7 . When the right hand armature of the relay R_7 operates the ground is removed from the winding of the relay R_4 which there-

upon is restored to its normal unoperated position, and contact 25 will be closed. It should be noted that the potential of the battery B_1 at office A is applied across the line L_1 at all time except when the ringing key of the same cord circuit is operated. Therefore, when contact 19 of relay R_7 is closed, current will flow from the said battery over the tip side of line L_1 to point 26 thence through contact 19, the series contacts of keys K_3 , K_4 and K_5 through the impedance coil 8 and winding of relay R_8 to the ring side of the line thereby causing the operation of the relay R_8 which, by the opening of its contact 20, causes the release of the marginal relay R_5 .

When the line L_1 has been connected to the desired subscriber's line by means of the cord circuit X the sleeves of the jacks J_2 and J_3 which are located at different switchboard positions from that in which the jack J_1 is located, will be energized by current from the battery B_4 associated with the cord circuit X . If the operators at the positions in which the jacks J_2 and J_3 are located desire to use the trunk L_1 they will first make the usual busy test upon the said line, which consists in touching the tip of the plug of a cord circuit to the sleeve of the jack of the desired line. When the operator at the position in which jack J_2 is located touches the tip of the plug P_2 to the sleeve of the jack J_2 the flow of current will take place from the sleeve of the said jack to ground, thereby charging the condenser C_4 . The charging of this condenser causes a flow of current in one of the windings of the transformer 21, which is connected in series therewith, which induces current in the other winding, which produces a click in the receiver of the operator's telephone set. By means of the resistance 23, which is connected in parallel with the condenser C_4 the condenser C_4 may be discharged, and is left in condition to be charged again when the tip of the plug is brought in contact with the sleeve of the jack J_2 . This arrangement provides a simple busy test circuit, which requires no relays in its operation, and which may therefore be readily maintained and operated since it has no moving parts requiring adjustment. It will also be seen in this particular form of busy test circuit that it is only necessary to bring the tip of a plug in contact with the sleeve of the desired jack in order to make the busy test, thereby avoiding the necessity of operating any keys of the switches. Furthermore, since the receiver of the telephone set is inductively related instead of being directly connected with the busy-test lead, the telephone circuit is insured against impairment if the busy test circuit becomes defective.

A further object of the invention is to

prevent the release of the marginal relay R_5 when a busy test is made for example upon jacks J_2 and J_3 by the cord circuits in those positions after the plug P_1 has 5 been inserted in jack J_1 in response to a call over line L_1 . If the operator at the office 10 desires to signal the operator at B after the line L_1 has been connected with another line at the office B by means of the cord circuit X, she performs some act which 15 opens the circuit previously traced from battery B_1 through the winding of the relay R_8 , such as operating the ringing key or withdrawing the plug P_5 from its jack. This 20 causes the release of the relay R_8 which by the closing of contact 20 allows current to flow from the battery B_2 through the right hand winding of the marginal relay R_5 , contact 20 and the right hand contact 25 of 25 relay R_7 to ground. Relay R_5 is thereby operated and by the closing of its right hand contact a circuit is established from battery B_4 conductors 16 and 17 to point 28 where the circuit divides, part of the current passing through winding of the relay R_2 and part through the lamp S_1 in parallel therewith, thence through the sleeve contacts of plugs P_1 and jack J_1 , part of the winding of the relay R_6 , contacts of the relays R_5 and 30 R_4 and the left hand winding of relay R_5 to ground. Sufficient current therefore will flow to cause the lamp S_1 to light, which indicates to the operator at B that the operator at the office A is signaling to her. If 35 the operator at B notices this signal promptly, she will operate the listening key K_1 , which bridges her telephone set across the conductors of the cord connected with the line L_1 . This operation of key K_1 opens 40 the circuit through the lamp S_1 at the contact 27 of key K_1 , thereby increasing the resistance of the circuit through the marginal relay R_5 to such extent that the relay R_5 fails to receive sufficient current to maintain it in its operated position, and it is 45 accordingly restored to its normal position. When the operators at the positions in which jacks J_2 and J_3 are located touch the tip contacts of the plugs P_2 and P_3 to the 50 sleeves of the jacks J_2 and J_3 respectively, a plurality of paths are provided from the sleeve of the jack J_1 to ground other than that provided through the winding of the marginal relay R_5 . If the resistance to 55 ground of the various busy test circuits is sufficiently low, sufficient current may be diverted from the path through the marginal relay R_5 so as to release the said relay thereby causing the lamp S_1 to be extinguished. Consequently the signal transmitted 60 from the office A to the office B might not be noticed by the operator at the latter office, and delay and confusion would thereby result. By making the resistance of the 65 busy tests circuits of proper magnitude based upon study of operating conditions, the possibility of releasing the marginal relay R_5 before the operator at B has responded to the signal of the lamp L_1 may be considerably minimized if not entirely 70 eliminated.

From the foregoing description of the invention and its mode of operation, it will be seen that it provides a simple and effective busy test arrangement which may be 75 readily maintained and is liable to cause less interruption to service than the busy test circuits heretofore employed. Although this invention has been shown embodied in a particular form, it is to be understood 80 that it is not limited to this single form, but is capable of embodiment in other and different forms within the scope of the appended claims.

What is claimed is:—

1. In a signaling system, the combination with a line circuit terminating in a plurality of multicontact jacks, of a marginal relay having one winding effectively connected with the sleeve contacts of the jacks at one end of said line circuit, a cord circuit having a supervisory signal and a source of current also connected with the sleeve contacts of the said jacks to which the said marginal relay is connected, whereby the said relay 90 may be locked up, a plurality of other cord circuits having busy-test branches connected with the tip conductors thereof, the electrical constants of which branches are so proportioned as to prevent the release of the said marginal relay when a predetermined number of busy tests are simultaneously made.

2. In a signaling system, the combination with a line circuit terminating at one end in a line jack and at the other end in line and multiple jacks, the sleeves of which are electrically connected together, and the tip and ring contacts being connected to the line conductors, a cord circuit having multicontact plugs for connection with the line jack at one end of said line circuit, a second cord circuit having multicontact plugs for connection with the line jack at the other end of said line circuit, and the said second circuit also having a supervisory signal and a source of current connected in the sleeve conductor thereof, a bridged relay and a marginal relay connected with the said line circuit, the said bridged relay being controlled 105 by the said first cord circuit, and the marginal relay being controlled by the said bridged relay and having a winding connected with the sleeves of the said line and the said multiple jacks, whereby the said relay 110 may be locked up, and the said signal operated by current from the said second cord circuit, and a plurality of other cord circuits having plugs for connection with the said multiple jacks and arranged for the 115 120 125 130

making of busy-tests upon the said line circuit by touching the tips of the said plugs to the sleeves of the said jacks, the said busy-test circuits having their electrical constants so chosen with respect to the constants of the marginal relay that the latter will not be released by the making of a predetermined

number of busy-tests simultaneously upon said line circuit.

In testimony whereof, I have signed my ¹⁰ name to this specification this 28th day of January 1920.

LEO H. DARROW.
